GOLF PRACTICE MAT

Forrest W. Pruitt, 1405 Gayla Drive,
Quincy, Ill. 62301

Filed July 21, 1970, Ser. No. 24,044

Term of patent 14 years

Int. Cl. D21—02

U.S. Cl. D34—5

FIG. 1 is a top plan view of a golf practice mat showing my new design; and

FIG. 2 is a reduced side elevational view thereof.

I claim:

The ornamental design for a golf practice mat, substantially as shown and described.
